REVERSIBLE ENGINE CONTROL EQUIPMENT

Ralph T. Whitney, Irwin, Pa., assignor to Westinghouse Air Brake Company, a corporation of Pennsylvania

Application June 18, 1949, Serial No. 100,069

12 Claims. (Cl. 123—41)

1

This invention relates to reversible engine control equipment and more particularly to control apparatus adjustable in accordance with direction of rotation of a reversible engine.

In certain fluid pressure control systems for controlling the reversing of a reversible internal combustion engine, a direction sensing interlock valve device is employed to effect holding of the fuel supply to the engine cut-off until the engine is rotating in its proper direction in accord with dictates from an operator's control device. Such an interlock device usually comprises a retractable shoe which is adapted to be brought into frictional contact with a rotatable part such as the engine crank shaft when in rotation to be biased in one direction or another according to direction of such rotation by a force generated by the frictional contact.

Heretofore in the control systems employing the above direction sensing interlock device, during reversing of the engine, the retractable shoe was brought into frictional contact with the engine crank shaft when same was rotating at relatively high speed and held in such contact until the engine was turning over in its reverse direction at relatively high speed. Such frictional contact of the retractable shoe with the rotating shaft resulted in unnecessary wear of the shoe and crank shaft. It is, therefore, a prime object of the present invention to provide an improved engine control apparatus employing a direction sensing interlock device in which wear of the retractable shoe will be minimized.

Other objects and advantages will become apparent from the following more detailed description of the invention.

In the accompanying drawing; Fig. 1 is a schematic view, partly in outline and partly in section, of one embodiment of the invention; Figs. 2, 3 are schematic views of portions of alternate embodiments of the invention; Fig. 4 is a detailed cross-sectional view of an inverse double check valve device employed in the structure shown in Fig. 2; and Fig. 5 is a detailed schematic cross-sectional view of a relay valve device one or several of which is or are employed in each of the embodiments shown in Figs. 1, 2 and 3.

DESCRIPTION OF FIG. 1

The reversible engine (not shown) may comprise the usual crank shaft 1, only a portion of which is shown in cross-section in the drawing, a cam shaft 2, only a portion of which is shown in outline in the drawing, and fuel control shaft 3.

2

The engine crank shaft 1 may be operably connected to the pistons (not shown) of the engine and operatively connected to means to be driven (not shown) such as a propeller or propellers on a ship, for example.

The engine cam shaft 2 is adapted to be driven in proper phase with the crank shaft 1 in the usual manner for operating conventional engine valve mechanism (not shown) to permit the engine to be started by means (not shown) for operation on fuel in either direction of rotation, to, for instance drive a ship ahead or astern. The cam shaft 2 may have the usual forward cams (not shown) to provide for operation in one or an ahead direction and the usual reverse cams (not shown) to provide for operation in the reverse or astern direction. In the well-known manner, the cam shaft 2 may be shifted axially in one direction to one position for rendering the forward cams effective to operate the engine valve or timing gear, and in the opposite direction to an opposite position for rendering the reverse cams effective to operate said gear.

The fuel control shaft 3 is operatively connected to fuel control valve means (not shown) for effecting regulation of the quantity of fuel supplied to the engine cylinders by way of fuel injection nozzles or the like (not shown). The control shaft 3 is secured for turning movement by such as a fuel control lever 4, which is adapted to be moved to a "Fuel off" position, indicated by a dot-and-dash line so titled in the drawing, in which position the fuel control valve means is so conditioned as to cut off supply of fuel to the engine cylinders, as is necessary to reverse the engine for example.

The control apparatus embodying the invention comprises a cam shift cylinder device 5 for effecting shift of the engine cam shaft 2 to condition the engine for operation in one direction or the other, a fuel cut-off cylinder device 6 for effecting movement of the fuel control lever 4 to its "Fuel off" position as in stopping or reversing the engine, an operator's control device 7 for controlling operation of the cam shift cylinder device 5 in reversing the engine and the fuel cut-off cylinder device 6 in stopping the engine, a directional interlock device 8 operable to sense the direction of rotation of the engine to control operation of the fuel cut-off cylinder device 6 in reversing the engine, a relay valve device 9 operable to render the fuel cut-off cylinder device responsive to either the directional interlock device 8, as in reversing the engine, or to

the operator's control device 7 as in stopping the engine, and a double check valve device 10 arranged in cooperation with certain control pipes to be described subsequently for controlling operation of the relay valve device 9.

The cam shift cylinder device 5 is shown in longitudinal section in Fig. 2 and for sake of illustration, may simply comprise a hollow cylindrical casing 15 having a cam shift piston 16 slidably disposed therein which is exposed on its one face to a chamber 17 and on its opposite face to a chamber 18. Fluid under pressure may be conveyed to and from the chamber 17 by way of such as an ahead control pipe 19 and to and from the chamber 18 by way of such as an astern control pipe 20. In response to supply of fluid under pressure to the chamber 17 by way of the ahead control pipe 19, while the chamber 18 is vented via the astern control pipe 20, the cam shift piston 16 will be caused to move in one direction to the position in which it is shown in Fig. 2, which may be called its "Ahead" position, so titled in the drawing. Conversely, in response to supply of fluid under pressure to the chamber 18 by way of the astern control pipe 20, while the chamber 17 is vented by way of the ahead control pipe 19, the piston 16 will be caused to move in the opposite direction to a position opposite to that in which it is shown in Fig. 2, which position may be called its "Astern" position indicated in the drawing by a dot-and-dash line so titled. The cam shift piston 16 is operatively connected to the engine cam shaft 2 through the medium of a rod 25 which extends outwardly in an accommodating opening in the end wall of the casing 15. When the cam shift piston 16 is caused to assume its "Ahead" position, the engine cam shaft 2 will be caused to assume its corresponding position to condition the engine for operation in its forward or ahead direction, and when the cam shift piston is caused to assume its "Astern" position, the engine cam shaft 2 is caused to assume its corresponding position to condition the engine for operation in its reverse or astern direction.

The fuel cut-off cylinder device 6, for sake of illustration, may comprise a hollow cylindrical casing 30 having a fuel cut-off piston 31 slidably disposed therein. Piston 31 is exposed at its one face to a pressure chamber 32 and at its opposite face to a spring chamber 33 which latter chamber is constantly open to atmosphere. A stop rod 34, attached to piston 31, extends outwardly through an accommodating opening in one end wall of the casing 30 for engagement with the fuel control lever 4. When fluid under pressure is supplied to the pressure chamber 32, the piston 31 will be caused to assume such as the position in which it is shown in the drawing, with the stop rod 34 in engagement with the fuel control lever 4 and holding same in its "Fuel off" position. Upon release of fluid under pressure from the pressure chamber 32, the piston 31 will be moved in the direction of said chamber 32 by a compression spring 35 in chamber 33 to a position defined by contact with such as a shoulder 36 in which position of said piston the stop rod 34 will be retracted away from the fuel control lever 4 to allow same to be moved in the direction of a "Full fuel" position by means of such as a speed governor device (not shown) for effecting supply of fuel to the engine.

The operator's control device 7 may be substantially like that shown and described in detail in United States Patent No. 2,413,390 issued to

Roy R. Stevens, December 31, 1946, and assigned to the assignee of the present application. For a detailed description of such a device 7, reference may be made to the above patent.

Briefly, the operator's valve device 7 comprises valve means (not shown) for controlling supply of fluid under pressure from such as a reservoir 41 by way of a control supply pipe 40 selectively to the ahead control pipe 19, the astern control pipe 20 and to a start control pipe 42 and release of fluid under pressure therefrom as well as for effecting variation in pressure of fluid in a speed control pipe 43. An operator's control lever 44 is provided for controlling operation of the valve means comprised in the device 7.

The operator's control device disclosed in the above-mentioned patent is employed in systems for controlling the starting, stopping, running, reversing, etc. of a reversible engine, but since the function and operation of the invention does not involve the use of more than the ahead and astern control pipes 19 and 20, only those positions of the operator's control lever 44 of device 7 for controlling selective establishment of pressure in said pipes 19 and 20 will be described in the present application.

In operation of the control valve device 7, the operator's lever 44 is movable to a "Stop" position in which it is shown in the drawing and in which position both the ahead and astern control pipes are vented to atmosphere. The operator's control lever 44 may be moved out of its "Stop" position in one direction indicated in the drawing by an arrow and a legend "Ahead" to effect supply of fluid under pressure from the control supply pipe 40 to the ahead control pipe 19 while maintaining the astern control pipe 20 vented to atmosphere. The operator's control lever 44 may also be moved out of its "Stop" position in the opposite direction indicated in the drawing by an arrow and a legend "Astern" to effect supply of fluid under pressure from pipe 40 to the astern control pipe 20 while the ahead control pipe 19 is maintained vented to atmosphere. The return of the operator's control lever 44 to "Stop" position from either "Ahead" or "Astern" will effect simultaneous venting of both the ahead and astern control pipes 19 and 20. In reversing the engine, the operator's control lever 44 may be moved from a position on whichever side of "Stop" position it may be in to a position on the opposite side of "Stop" position without pause in said "Stop" position to effect a reversal in pressure conditions in the ahead and astern control pipes 19 and 20. For example, the control lever 44 may be moved continuously from a position on the "Ahead" side of "Stop" position to a position on the "Astern" side of "Stop" position thereby effecting venting of the previously charged ahead control pipe 19 and pressurization of the previously vented astern control pipe 20, the effect on pressure conditions in pipes 19 and 20 of moving handle 44 through "Stop" position during the above movement may be neglected due to the fact that the lever 44 will occupy "Stop" position only momentarily in passing through.

The directional interlock device 8 in the usual form comprises a casing having two poppet valves 131 and 132 contained in chambers 133 and 134 respectively. The poppet valves 131 and 132 are arranged side by side with parallel extending fluted stems 135 and 136, respectively, which extend into a delivery chamber 137 com-

mon to both. The valves 131 and 132 are provided to control communication between the chambers 133 and 134, respectively, and the chamber 137. A spring 138 in each of the chambers 133 and 134 acts on the respective valve 131, 132 to urge same toward a closed position, in which position the valve 131 is shown in the drawing.

The valve stems 135 and 136 engage, respectively, two spaced apart operating plungers 139 and 140 which are slidably mounted in the casing and which are provided with stems 141 and 142 extending outwardly through the casing. Two rockable cams 144 and 145, fulcrumed on pins secured to the casing, are provided for actuating the plungers 141 and 142, respectively. These cams may be identical but reversely arranged, and each is operatively connected to the respective plunger 141, 142 through the medium of a follower element 147 rockably mounted on a pin secured in the casing. Each of the cams 144 and 145 is provided with a surface 149 which, when in engagement with the respective element 147, will unseat the respective valve 131 or 132. Adjacent to the surface 149, each cam is provided with a recess 150 which is adapted to receive the respective element 147 to permit movement of the respective plunger 139 or 140 by a respective spring 151 to a position to permit closure of the respective valve 131 or 132 by the respective spring 138.

The two cams 144 and 145 are operatively connected for movement in unison by a link 152, and since the cams are reversed as above mentioned, movement of the link and cams to the position in which they are shown in the drawing will effect opening of the valve 132 and closure of the valve 131, while movement of said link and cams in a clockwise direction, as viewed in the drawing, to a position in which the surface 149 on the cam 144 engages the respective element 147 will effect opening of the valve 131 and closing of the valve 132.

The directional interlock device 8 further comprises a shoe actuating piston 154 which is operatively connected to the link 152 by means of a piston rod 155, which extends through a non-pressure chamber 156 at one side of said piston. At the opposite side of the piston 154 there is a piston or pressure chamber 157. The opposite or outer end of the piston rod 155 is connected by a pin 159 with a friction shoe 161 which is adapted and arranged for frictional engagement with the outer surface of the crank shaft 1. The piston rod 155 is also operatively connected by means of pin 159 to one end of a link 163, the opposite end of which is operatively connected to the link 152 by means of a pin 163'.

The piston rod 155 is capable of side movement in the non-pressure chamber 156 from the position in which it is shown in the drawing, and which is defined by contact with a surface 164 in the casing, to a position in which said rod engages a surface 165 in the casing. Adjacent to the surface 165, the casing is provided with a pin 166 which is arranged to engage in one of two recesses 167, 168 according to whether or not the piston rod is in the position in which it is shown in the drawing or is in its opposite position engaging the surface 165.

When fluid under pressure is supplied to the pressure chamber 157, in a manner which will be described herein subsequently, the piston 154 will move the friction shoe 161 into engagement with the engine crank shaft 1, which, if rotating,

will bias the rod 155 toward one or the other of surfaces 164 or 165, according to the direction in which said shaft is turning. At the time of engagement of the shoe 161 with the shaft 1, the link 163 will be disposed away from the pin 166, so that the rod 155 is free for sidewise movement to effect positioning of the cams 144 and 145 accordingly. If, at the time of engagement of the shoe 161 with the shaft 1, said shaft is rotating in its forward or ahead direction, the rod 155 will be biased to the position in which it is shown in the drawing in leaning engagement with the surface 164, and the cams 144 and 145 therefore will be caused to assume the positions in which they also are shown in the drawing with the valve 131 consequently closed and the valve 132 open. If, conversely, the shaft 1 is rotating in the reverse or astern direction at the time of engagement by the shoe 161, the rod 155 will be caused to assume its opposite position in leaning engagement with the surface 165, thereby effecting shift of the cams 144, 145 to their positions in which the valve 132 is closed and the valve 131 is opened. If, however, at the time that the shoe 161 engages the shaft 1, said shaft is static, the rod 155 will remain in leaning engagement with whichever of the shoulders 164 or 165 it may be in such engagement with at the time. Upon release of fluid under pressure from the chamber 157, a spring 170 will move same in the direction of said chamber to a rest position in which it is shown in the drawing, while the shoe 161 will thereby be moved to a corresponding rest position seated on accommodating shoulders 171 formed in the casing. The link 163 will return into contact with the pin 166 which will project into one or the other of the recesses 167 or 168 to lock the piston rod 155, cams 144, 145, and the valves 131, 132 in the positions which they were caused to assume when the shoe 161 last engaged the shaft 1 when rotating.

Referring to Fig. 5, for sake of illustration, schematically the relay valve device 9 shown in outline in Fig. 1 may comprise a casing 200 having a diaphragm 201 disposed therein subject to pressure of fluid in a diaphragm control chamber 202 at its one side and to atmospheric pressure in a chamber 203 at its opposite side. Also formed in the casing are chambers 204, 205 and 206, chamber 204 being separated from the chamber 203 by a partition 207 and from the chamber 205 by a partition 208. A partition 209 separates the chamber 205 from the chamber 206. A valve 210 is disposed in the chamber 204 for controlling communication between the chamber 205 and said chamber 204. The valve 210 may be secured to a fluted stem 211 slidably mounted in a suitable bore extending through the partition 209, a valve seat being formed at the end of the bore that opens into the chamber 204 for accommodating the valve 210. A valve 212, similar to the valve 210, is disposed in the chamber 206 for controlling communication between the chamber 205 and said chamber 206. The valve 212 is attached to a fluted stem 213 which is slidably disposed in a suitable bore extending through the partition 209, a valve seat being formed in the end of said bore opening into the chamber 206 to accommodate the valve 212. Both of the fluted stems 211 and 213 project into and meet in the chamber 205. A bias spring 214 is disposed in the chamber 206 arranged to urge the valve 212 towards its seat, and at the same time, through engagement of stems 211 and 213, to urge the valve 210 away from its seat. The valve 210 is operably con-

nected to the diaphragm 201 by means of a rod or stem 215 which extends through a bore in the partition 207. A control spring 216 is provided in the chamber 203 to oppose deflection of the diaphragm 201 in the direction of the chamber 203.

In operation of the relay valve device shown in section in Fig. 5, with the chamber 203 constantly open to atmosphere by way of such as a casing port 203', upon supply of fluid under pressure to the control chamber 202, the diaphragm 201 will deflect in the direction of the chamber 203 against opposition of the control spring 216 and the bias spring 214 and will cause seating of the valve 210 and unseating of the valve 212. With the valve 210 closed and the valve 212 open, the chamber 205 will be closed to the chamber 204 and open to the chamber 206. Upon subsequent venting of fluid under pressure from the control chamber 202, the bias spring 214 and the control spring 216 will return the diaphragm 201 and valves 210 and 212 to the positions in which they are shown in the drawing; the valve 212 being seated and the valve 210 being unseated. With the valve 210 unseated and the valve 212 seated, the chamber 205 will be closed to the chamber 206 and open to the chamber 204.

Hereinafter, in describing operation of the relay valve device 9 shown in outline in Fig. 1, as well as those to be described hereinafter and shown in Figs. 2 and 3, when the control chamber is vented to atmosphere and the valves 210 and 212 are consequently unseated and seated, respectively, resultant connection between the chamber 205 and the chamber 204 by way of the unseated valve 210 will be referred to as a communication 118 which is represented symbolically in the drawing in each instance by a solid line appearing within the outline of the relay valve device. Similarly, when the valve 210 is seated and the valve 212 is unseated as a consequence of supply of fluid under pressure to the control chamber 202 in the relay valve device, the resultant connection between the chamber 205 and the chamber 206 by way of the unseated valve 212 will be referred to as a communication 119, indicated symbolically in the drawing by a dash line appearing within the general outline of the device.

The double check valve device 10 shown in outline in Fig. 1 may be of any well-known structure and for sake of illustration may simply comprise a casing having a piston valve (not shown) slidably mounted therein to control communication between one or the other of two opposite like inlet openings and an outlet opening.

In operation of the double check valve device 10, when fluid under pressure is supplied to one of its inlet openings with the other of said inlet openings vented, the piston valve will be caused to assume a position which closes off from the outlet opening whichever of said inlet openings is vented and opens to said outlet opening whichever of said inlet openings is pressurized. Upon venting of both inlet openings to atmosphere, the outlet opening will vent to atmosphere via one or the other of said inlet openings depending upon the position of the piston valve at the time.

In the relay valve device 9, its control chamber 202 is connected to the outlet opening of the double check valve device 10 by way of a pipe 300, its chamber 204 is connected to a branch of the control supply pipe 46, its chamber 205 is connected to the pressure chamber 32 in the fuel cut-off cylinder device 6 by way of such as a pipe 301, and its chamber 206 is connected to the de-

livery chamber 137 in the directional interlock device 8 by way of such as a delivery pipe 302.

In the double check valve device 10, its outlet opening is connected to the pipe 300 as aforementioned, and its inlet openings are connected to the ahead and astern control pipes 19 and 20 respectively.

According to a feature of the invention, the pressure chamber 157 in the directional interlock device 8 is connected to the delivery chamber 137 therein by way of conduits or pipes 305 and 305' connected respectively to chambers 137, 157 and to each other to allow for automatic release of fluid under pressure from the chamber 157 upon rotation of the engine crank shaft in accord with dictates of the operator's control device 7, as will be described in detail subsequently.

Operation—Fig. 1

Assume now that the operator's lever 44 of the operator's control device 7 is in its "Stop" position, with both the ahead and astern control pipes 19 and 20 consequently vented to atmosphere. The pipe 300, hence the control chamber 262 in the relay valve device 9, will be vented to atmosphere by way of the double check valve device 10 and one or the other of the now vented control pipes 19 and 20. With its control chamber thus vented to atmosphere, the relay valve device 9 will be positioned with its communication 118 established, connecting the pipe 301 to the control supply pipe 46 so that the chamber 32 in the fuel cut-off cylinder device 6 will be charged with fluid under pressure. The fuel cut-off piston 31 consequently will be in the position in which it is shown in the drawing, with the stop rod 34 holding the fuel control lever 4 in its "Fuel off" position to prevent supply of fuel to the engine at this time.

Assume further that the engine was last operating in its forward, or ahead, direction. The cam shift piston 16 in the cam shift cylinder device 5 will be in its "Ahead" position in which it is shown in the drawing with the engine cam shaft 2 also correspondingly positioned to condition the engine for operation in its forward direction. Both of the chambers 17 and 18 in the cam shift cylinder device 5 will be vented to atmosphere at this time by way of the now vented ahead and astern control pipes 19, 20 so that the cam shift piston 16 and engine cam shaft 2 will remain static.

After previous operation of the engine in its ahead direction, the directional interlock device 8 will be in the position in which it is shown in the drawing, with the valve 132 open, and the valve 131 closed. Its delivery chamber 137 therefore will be disconnected from the ahead control pipe 19 and connected to the now vented astern control pipe 20 by way of the unseated valve 132. The pressure chamber 157 in the directional interlock device 8, being connected to the chamber 137, therefore will be vented at this time by way of the astern control pipe 20. With pressure chamber 157 vented, the piston 164 will be in its rest position in which it is shown in the drawing with the friction shoe 161 consequently in a retracted rest position seated on shoulders 171 and disposed away from the now static engine crank shaft 1. Since when the shoe 161 was last in engagement with the engine crank shaft 1 said shaft was turning in its ahead direction as assumed, the piston rod 165 will be locked by pin 166 in notch 168 in the position 75 in which it is shown in the drawing in leaning

engagement with the surface 164, thereby holding, through respective position of the cams 144, 145, the valve 132 unseated and allowing the valve 131 to be in its seated position by virtue of the force of the respective compression spring 138.

Now assume that, as in the usual manner, that the operator's lever 44 is moved out of "Stop" position in the "Ahead" direction to effect starting of the engine in its ahead direction by means (not shown). In response to this movement of the operator's lever 44, supply of fluid under pressure to the ahead control pipe 19 will be effected by the device 7. Fluid under pressure from the ahead control pipe 19 will flow into the chamber 17 in the cam shift cylinder device 5, but since the cam shift piston 16 is already in its "Ahead" position at the time, said piston will remain static with the engine cam shaft 2 remaining in its corresponding position conditioning the engine for operation in its ahead direction. From the ahead control pipe 19, fluid under pressure will also flow to the control chamber 202 in the relay valve device 9 to cause same to disestablish its communication 118 which connects the pipe 301 to the control supply pipe 40 and to establish its communication 119 which connects said pipe 301 to the pipe 302 thence to the chamber 137 in the directional interlock device 8. Since, as aforementioned, the directional interlock device 8 is in its ahead position at this time with its valve 131 closed and its valve 132 open, fluid under pressure will release from the chamber 32 in the fuel cut-off cylinder device 6 by way of the pipe 301, the newly established communication 119 in the relay valve device 9, the pipe 302, chamber 137 in the directional interlock device 8, the unseated valve 132 and chamber 134 therein, and the astern control pipe 20. The fuel cut-off piston 31 will then be caused to assume its release position in which the stop rod 34 is disposed away from the fuel control lever 4 to allow the fuel control shaft 3 to be positioned to effect supply of fuel to the engine.

Fluid under pressure supplied to the ahead control pipe 19 will also flow into the chamber 133 in the directional interlock device 8, but such fluid under pressure will not reach its chamber 131 since its valve 131 is seated.

It should be pointed out that during the time that the above is occurring, the pressure chamber 157 in the directional interlock device 8 remains vented by way of the pipe 305, the pipe 305, and the chamber 137 so that the friction shoe will remain in its rest position disposed away from the engine crank shaft 1.

It will be seen from the foregoing description that when the operator's lever 44 is moved out of "Stop" position to effect starting of the engine in the same direction in which it last operated, the fuel cut-off cylinder device 6 is released, while the piston 154 in the directional interlock device 8 remains in its rest position, thereby conserving fluid under pressure over former systems employing such a device in a manner which caused operation of the piston 154 and engagement of shoe 161 with shaft 1 when starting the engine in the same direction in which it last operated. In addition to conservation of fluid under pressure, in employing the directional interlock device 8 in fashion as illustrated in the present application, what is even more important, the wear on the shoe 161 is greatly reduced over the previous methods of employ-

ing such interlock device, since it frequently occurs that the engine is restarted for operation in its previous direction of operation particularly when operating in its ahead direction.

5 As is the usual practice, to stop the engine, the operator's control lever 44 will be returned to its "Stop" position, effecting venting of the ahead control pipe 19 to atmosphere along with the astern control pipe 20 already so vented. Fluid under pressure will then release from the chamber 17 in the cam shift cylinder device 5, directly by way of the ahead control pipe 19, and from the control chamber 202 in the relay valve device 9 by way of the pipe 300, double check valve device 18 and the now vented ahead control pipe.

10 Upon the above venting of fluid under pressure from the chamber 17 in the cam shift cylinder device 5, the cam shift piston 16 and hence the engine cam shaft 2 will remain static in position to condition the engine for operation in its ahead direction.

15 Venting of fluid under pressure from the control chamber 202 in the relay valve device 9, however, renders said device responsive to disestablish its communication 119 which connects the pipe 301 to the pipe 302 and to establish its communication 118 which connects said pipe 301 to the control supply pipe 40, whereupon fluid under pressure will flow thereby to the chamber 32 in the fuel cut-off cylinder device 6 to cause the stop rod 34 to assume the position in which it is shown in the drawing, moving the fuel control lever 4 to its "Fuel off" position to terminate supply of fuel to the engine for stopping same from operation in its ahead direction. All parts of the apparatus will now assume the positions in which they were described previously with the engine stopped subsequent to its operation in the ahead direction.

20 Now assume that, with the engine stopped after previous operation in its ahead direction and with the operator's control lever 44 in its "Stop" position, it is desired to effect starting of the engine in a direction opposite to that in which it last operated, in its astern direction for example. The operator's lever 44 will be moved out of its "Stop" position in the direction of "Astern" to effect supply of fluid under pressure to the astern control pipe 20 while maintaining the ahead control pipe 19 vented as in "Stop" position.

25 Fluid under pressure thus supplied to the astern control pipe 20 will flow to the chamber 18 in the cam shift cylinder device 5 and to the chamber 157 in the directional interlock device 8 by way of chamber 134, unseated valve 132, delivery chamber 137 and the pipe 305, 305' therein, and to the control chamber 202 in the relay valve device 9 by way of the double check valve device 18 and the pipe 300.

30 In response to supply of fluid under pressure to chamber 18 in cylinder device 5, with its chamber 17 vented via the astern control pipe 20, the cam shift piston 16 will be caused to assume its "Astern" position opposite to that in which it is shown in the drawing to shift the engine cam shaft 2 to its corresponding position to condition the engine for operation in its astern direction.

35 In response to fluid under pressure supplied as above to its control chamber 202, the relay valve device 9 will respond to disestablish its communication 118 which connects the pipe 301 to the control supply pipe 40 and to establish its communication 119 which connects the now charged delivery chamber 137 in the directional interlock device 8 to the pressure chamber 32 in the

11

fuel cut-off cylinder device 6, via pipes 301 and 302, so that at this time the fuel control lever 4 will be held in its "Fuel off" position by effect of pressure of fluid held in the chamber 32.

Pressure of fluid supplied to the delivery chamber 137 in the directional interlock device 8 from the now charged astern control pipe 20 will also flow via pipe and passage 305 to the pressure chamber 157 therein. In response to supply of fluid under pressure to the chamber 157, the piston 154 will be caused to move the friction shoe 161 into engagement with the engine crank shaft 1 which may yet be static at the time. With the friction shoe 161 in engagement with the engine crank shaft 1, when the engine is caused to turn over in its astern direction, said shoe in being biased to follow movement of the crank shaft will cause, through shift in position of link 152 and cams 144, 145, seating of the valve 132 and unseating of the valve 131, whereupon fluid under pressure will release from the pressure chamber 32 in the fuel cut-off cylinder device 6 by way of pipe 301, communication 119 in relay valve device 9, pipe 302, chamber 137 in directional interlock device 8, the unseated valve 131 and the ahead control pipe 19 to allow stop rod 34 to be retracted from the fuel control lever 4 to allow the fuel control shaft 3 to be moved to effect supply of fuel to the engine. Also, upon closure of the valve 132 and opening of the valve 131 in the directional interlock device 8, fluid under pressure in the chamber 157 therein will release to atmosphere by way of the pipe 305', the pipe 305, the chamber 137, the unseated valve 131, chamber 133, and the vented astern control pipe 20. Upon release of fluid under pressure from the pressure chamber 157, the piston 154 will be caused by action of the spring 170 to return to its rest position, with rod 155 in leaning engagement with surface 165 and the link 152 locked in position by pin 166 in the notch 167 to hold the cams 144, 145 so positioned as to hold the valve 131 unseated with the valve 132 seated.

It will be seen that when the engine is started in a direction opposite to that in which it was last operated, astern after operation ahead, for example, as above described, according to a feature of the invention, with the friction shoe 161 held in contact with the engine crank shaft 1 by pressure of fluid in the pressure chamber 157, by virtue of the connection 305 with the chamber 137, as soon as the shaft 1 is started to turn in its new, or astern, in the present instance, direction, fluid under pressure in said pressure chamber 157 is automatically released by way of said chamber 137 to allow spring 170 to move the friction shoe 161 to its retracted position away from the rotating shaft 1. It will be appreciated that such retraction of shoe 161 will be effected automatically upon initial turning movement of the shaft 1 before same is actually rotating at any appreciable speed, thereby preventing unnecessary wear on the shoe that otherwise occurs in previous arrangements employing a directional interlock device in such a fashion as allows the shoe to remain in engagement with the shaft for a considerable time after rotation in its new direction.

To stop the engine operating in its astern direction, in the usual manner, the operator's lever 44 is moved to whatever position it may be occupying at the "A stern" side of "Stop" position to the "Stop" position, thereby effecting venting of the astern control pipe 20 along with the ahead control pipe 19 already so vented.

12

Fluid under pressure will then release from the control chamber 202 in the relay valve device 9 by way of the pipe 300 and double check valve device 10 to cause supply of fluid under pressure 5 from the control supply pipe 40 to the chamber 32 in the fuel cut-off cylinder device 6 through establishment of the communication 118 in said relay valve device. The fuel cut-off cylinder device 6 will then respond to effect cut off of supply of fuel to the engine through movement of the fuel control lever 4 to its "Fuel off" position, as will be appreciated from previous description. The engine will then come to a stop with the cam shift piston 16 remaining in its "Astern" position and 15 the engine cam shaft 2 remaining in its corresponding position, conditioning the engine for operation in its astern direction. The directional interlock device 8 will also remain in its astern position with shoe 161 retracted and valves 131, 20 132 open and closed, respectively.

It will be appreciated that in operating the control apparatus to effect starting of the engine ahead after previous operation astern, the directional interlock device 8 will respond in manner 25 as aforescribed, retracting its shoe 161 upon initial turning movement of the shaft 1 in its new, or ahead direction before the shaft is yet turning at any appreciable speed.

Now assume that the engine is running in its 30 ahead direction with the operator's lever 44 positioned at the "Ahead" side of "Stop" position and with the ahead control pipe 19 charged with fluid under pressure and the astern control pipe 20 vented. As aforescribed, the cam shift piston 16 and engine cam shaft 2 will be in their respective ahead positions, the relay valve device 9 will be positioned with its communication 119 established, the directional interlock device 8 will be in its ahead position with the valve 131 seated 35 and the valve 132 unseated so that chamber 137 and the valve 132 connected to the vented astern control pipe 20. The chamber 157 in the directional interlock device 8 and the chamber 32 in the fuel cut-off cylinder device 6 will be vented to atmosphere by way of the chamber 137 in said device 8. The friction shoe 161 in the directional interlock device 8 therefore will be in its retracted position away from the rotating engine crank shaft and the fuel cut-off cylinder device 6 will be in its released position with the stop rod 34 disposed 40 away from the fuel control lever 4.

Now assume that in the usual manner, the operator's lever 44 is moved from its position on the "Ahead" side of "Stop" position directly to a position 45 on the "A stern" side of "Stop" position for effecting a reversal in the direction of operation of the engine from ahead to astern, for example. Venting of the ahead control pipe 19 and charging of the astern control pipe 20 is thereby effected.

Venting the ahead control pipe 19 and charging the astern control pipe 20 will not effect the status of the relay valve device 9, since its control chamber 202 will remain pressurized when either one or the other of the control pipes 19 or 20 is pressurized by way of the double check valve device 10 and the pipe 300. The communication 119, therefore is maintained established, connecting the chamber 32 in the fuel cut-off cylinder device 6 to the chamber 137 in the directional interlock device 8 by way of the pipes 301 and 302.

Fluid under pressure from the astern control pipe 20 will flow by way of the chamber 134, the unseated valve 132, into the chamber 137 in the directional interlock device 8, thence to the pressure chamber 32 in the fuel cut-off cylinder de-

13

vice 6 to cause cut-off of supply of fuel to the engine, as will be appreciated from previous description, and to the pressure chamber 157 in said device 8 to cause the friction shoe 161 to be brought into engagement with the crank shaft 1 rotating in its ahead direction. While the crank shaft continues to turn in its ahead direction, the valves 131, 132 in the directional interlock device 8 will remain closed and open, respectively, as will be appreciated from previous description.

At the same time, fluid under pressure supplied to the astern control pipe 20 will flow into the chamber 18 in the cam shift cylinder device 5 as fluid under pressure from the chamber 17 releases by way of the vented ahead control pipe 19, so that the cam shift piston 16 will be caused to shift the engine cam shaft 2 from its ahead to its astern position to condition the engine for operation in its astern direction.

Upon completion of the above shift in position of the engine cam shaft 2, the starting means (not shown) may be brought into operation to oppose further rotation of the engine in its original or ahead direction and to turn the engine over in its new or astern direction.

Upon initial turning movement of the engine, hence crank shaft 1, in the astern direction, the friction shoe 161 in contact with said shaft will cause rocking of the rod 155 from its position in leaning engagement with the surface 164 to its opposite position in leaning engagement with the surface 165, causing through resultant movement of the link 152, rocking movement of the cams 144, 145 and thereby unseating the valve 131 and allowing the respective spring 138 to seat the valve 132, as will be appreciated from previous description.

Upon closing of the valve 132 and opening of the valve 131 in the device 8 its chamber 137 will become vented to atmosphere via the unseated valve 131 and the now vented ahead control pipe 19 so that fluid under pressure will release from the pressure chamber 157 beneath piston 154 in device 8 to allow for retraction of friction shoe 161 to its rest position disposed away from the crank shaft 1 being brought into rotation, and fluid under pressure will also simultaneously release from the pressure chamber 32 in the fuel cut-off cylinder device 6 to allow for movement of the fuel control shaft 3 for effecting supply of fuel to the engine, as will be appreciated from previous description. It should be recalled that at the time that the chamber 137 in the directional interlock device 8 is vented via the ahead control pipe, the chamber 32 in the fuel cut-off cylinder device 6 is connected to said chamber 137 by way of the pipe 301, communication 119 in the relay valve device 9, and the pipe 302.

It will be seen now that in effecting reversal in direction of operation of the engine, the friction shoe 161 of the directional interlock device 8 is moved into frictional engagement with the engine crank shaft 1 while it is still turning in its original or ahead direction, and automatically retracted to its rest position disposed away from said shaft 1 substantially upon its initial turning movement in the new or astern direction, to prevent prolonged engagement of said shoe with the shaft when rotating in its new direction, thereby reducing the wear on said shoe.

Reversal in operation of the engine from astern to ahead may be effected in similar fashion, with automatic retraction of the shoe 161 away from the shaft 1 upon its initial turning movement in its new direction.

14

Termination of operation of the engine in its astern direction will be effected in fashion as aforescribed, through movement of the operator's control lever 44 from its position at the "Astern" side of "Stop" position to said "Stop" position.

DESCRIPTION OF FIG. 2

The structure shown in Fig. 2 comprises a relay valve device 400, which may be similar schematically to the relay valve device shown in detail in Fig. 5, and an inverse double check valve device 401 arranged to delay supply of fluid under pressure from the chamber 137 to the chamber 157 in the directional interlock device 8 during reversal of the engine until the engine cam shaft 2 has been shifted in order to reduce the length of time that the shoe 161 of device 8 remains in contact with the shaft 1 when rotating in its original direction, prior to automatic retraction of said shoe upon initial turning movement of said shaft in its new direction.

Referring to Fig. 2, in the relay valve device 400, its chamber 204 is connected to atmosphere by way of such as a pipe 350, its chamber 205 is connected to the pipe 305', hence to the pressure chamber 157 in the interlock device 8, and its chamber 206 is connected to the pipe 305, hence to the chamber 137 in said device 8.

In response to supply of fluid under pressure to its control chamber 202 by way of such as a pipe 321, the relay valve device 400 will respond to establish its communication 119 connecting the pipe 305' to the pipe 305 and thereby connecting the chambers 157 and 137 in the directional interlock device 8. In response to release of fluid under pressure from its control chamber 202, the relay valve device 400 will disestablish its communication 119 and establish its communication 118 connecting the pipe 305', hence chamber 157 in device 8 to atmosphere via pipe 350.

Referring to Fig. 4, the inverse double check valve device 401 shown in outline in Fig. 2 may comprise a casing 323 having a bushing 324 which is encircled midway between its ends by an annular chamber 325 connected to the pipe 321. The bushing 324 is provided interiorly and midway between its ends with a bridge having an axial bore 326 open to chamber 325 through a plurality of radial openings 327. At one end of the bore 326 is an annular seat arranged for sealing engagement by a valve 328 contained in a chamber 329, while at the opposite end of said bore is an oppositely arranged annular seat provided for sealing engagement by a valve 330 contained in a chamber 331. The two valves 328 and 330 are connected for movement in unison by a stem 332 extending with clearance through the bore 326. This stem is of such construction as will allow flow of fluid under pressure past either valve 328 or 330, when unseated, through the bore 326 to the annular chamber 325.

The chamber 331 is connected to a pipe 333 arranged to be connected to the chamber 18 in the cam shift cylinder device 5 just to the left of the cam shift piston 16 when said piston is in its "Astern" position opposite to that in which it is shown in the drawing. The chamber 329 in the inverse double check valve device 401 is connected to a pipe 334 arranged to be opened to the chamber 17 in the device 5 just to the right of the cam shift piston 16 when said piston is in its "Ahead" position in which it is shown in the drawing.

In operation of the inverse double check valve

15

device 401, when only one of the pipes 333, 334 is charged with fluid under pressure, the respective valve 328 or 330 will close to prevent fluid under pressure from flowing into the pipe 321 while same will remain vented by way of the other unseated valve 329 or 330 and the respective uncharged pipe 333 or 334. When both of the pipes 333 and 334 become charged, fluid under pressure will flow from one or the other of these pipes by way of whichever of the valves 328, 330 is unseated into the pipe 321 to the control chamber in the relay valve device 400.

Operation—Fig. 2

In operation of the control system employing the structure shown in Fig. 1 modified as shown in Fig. 2, assume that the engine is stopped after previous operation in its ahead direction, for example. All parts of the apparatus shown in Fig. 1 will be positioned as previously described and in which they are shown in the drawing with the operator's control lever 44 in its "Stop" position. In Fig. 2, both pipes 333 and 334 connected to the inverse double check valve device 401 will be vented by way of the chamber 17 in the cam shift cylinder device 5 and the ahead control pipe 19 which is vented via the control device 7 in Fig. 1 at this time, as will be recalled from earlier description. With both the pipes 333, 334 thus vented as above, the pipe 321 and hence the control chamber in the relay valve device 400 will be vented by way of the inverse double check valve device 401 and the pipe 321, as will be appreciated from the previous description of operation of said device 401. With its control chamber thus vented, the relay valve device 400 will be in its position in which its communication 118 is established so that the chamber 157 in the interlock device 8 in Fig. 1 will be vented to atmosphere via the pipe 305' now connected to the pipe 350. The piston 154 and shoe 161 in the device 8 will both be in their respective repose positions previously described.

Now assume that the operator's control lever 44 in Fig. 1 is moved to a position on the "Ahead" side of "Stop" position to effect operation of the engine in the same, or ahead as assumed, direction in which it last operated. The ahead control pipe 19 becomes supplied with fluid under pressure as aforescribed while the astern control pipe 20 remains vented. From the ahead control pipe, fluid under pressure will flow to the chamber 133 in the directional interlock device 8, but is prevented from reaching the chamber 137 therein by the seated valve 131, and said chamber 137 will remain vented by way of the unseated valve 132 and the astern control pipe 20. Fluid under pressure also will flow from the ahead control pipe 19 into the chamber 17 in the cam shift cylinder device 5, through one or the other of the pipes 333 or 334, through the inverse double check valve device 401 and the pipe 321 to the control chamber in the relay valve device 400 which will respond to disestablish its communication 118 and to establish its communication 119. The chamber 157 in the interlock device 8 then becomes connected to the now vented chamber 137 therein by way of the pipe 305', communication 119 in relay valve device 400 and the pipe 305. The piston 154 and shoe 161 in device 8 will both remain in their repose position at this time as starting means is brought into operation to turn the engine over in its ahead direction in ac-

16

cord with position of the operator's control lever 44.

In response to movement of the operator's control lever back to its "Stop" position in which both the ahead and astern control pipes 19, 20 become vented, the parts of the apparatus of Figs. 1, 2 will assume their respeceive positions as previously described as the engine comes to a stop.

10 Now assume that, with the engine stopped, after previous operation in its ahead direction, it is desired to start the engine operating in its astern direction through movement of the operator's lever 44 out of "Stop" position to a position on the "Astern" side of "Stop" position, thereby effecting supply of fluid under pressure to the astern control pipe 20 while maintaining the ahead control pipe 19 vented.

Fluid under pressure from the astern control pipe 20 will flow by way of the double check valve device 19 and the pipe 300 to the control chamber in the relay valve device 9 to cause same to establish its communication 119 connecting the pipes 301 and 302 to allow fluid under pressure from the astern control pipe to flow by way of the unseated valve 132 and chamber 137 in the directional interlock device 8 to the chamber 32 in the fuel cut-off cylinder device 6 to hold fuel supply cut-off to the engine.

20 At the same time, fluid under pressure from the astern control pipe 20 will flow into the chamber 18 in the cam shift cylinder device 5 whose chamber 17 will be vented via the ahead control pipe 19 at the time to cause movement of the cam shift piston 16 from its "Ahead" position, in which it is shown in the drawing, to its opposite "Astern" position to condition the engine for operation astern.

Just prior to movement of the cam shift piston 16 out of its "Ahead" position, both pipes 333 and 334 will be vented to atmosphere by way of chamber 17, then initial movement of said piston out of its "Ahead" position toward its "Astern" position will uncover the pipe 334 to the pressurized chamber 18 while the pipe 333 remains vented via chamber 17, and finally upon attaining its "Astern" position will uncover the pipe 333 to the pressurized chamber 18, so that both pipes 333, 334 then become charged with fluid under pressure.

40 It will be appreciated from previous description that at the time fluid under pressure is supplied to the chamber 18 in the cam shift cylinder device 5 with the chamber 17 vented to atmosphere to cause the piston 16 to move from its "Ahead" position to its "Astern" position, the pipe 321, hence the control chamber 202 in the relay valve device 400, will remain vented to atmosphere by way of the inverse double check valve device 401 until both pipes 333, 334 become charged with fluid under pressure upon attainment of the cam shift piston 16 in its "Astern" position.

55 It will be seen that during the time that the above shifting in position is occurring, with control chamber 202 in relay valve device 400 vented to atmosphere, its communication 119 will be maintained disestablished and its communication 118 established so that fluid under pressure supplied, as aforescribed, to the chamber 137 in the directional interlock device 8 may not reach the pressure chamber 157 by way of the pipe 305, and said pressure chamber 157 will remain vented by way of the pipe 305', said communication 118 in device 400 and the pipe 350.

At the time that the cam shift piston attains its new "Astern" position and the control chamber 202 in the relay valve device 400 becomes charged as aforescribed with fluid under pressure, said relay valve device will disestablish its communication 118 which connects the pipe 305' to atmosphere and will establish its communication 119 which connects the pipe 305' to the charged pipe 305. Fluid under pressure will then flow from the pipe 305 via the communication 119 in the device 400 and the pipe 305' to the pressure chamber 157 in the directional interlock device 8 to move the piston 154 to cause engagement of the shoe 161 with the engine crank shaft 1.

Also upon completion of shift of the cam shaft 2 by movement of the cam shift piston 16 to its "Astern" position, the starting means (not shown) will be brought into operation to turn the engine over in its new or astern direction. Upon initial turning movement of the shaft 1 in its new or astern direction, through resultant shift in position of the shoe 161 in engagement therewith, the valve 131 will be unseated and the valve 132 seated, whereupon fluid under pressure will release from the pressure chamber 157 in device 8 by way of the pipe 305', communication 119 in relay valve device 400, the pipe 305, said chamber 137, the unseated valve 131, chamber 133 and the vented ahead control pipe 19 to allow the shoe 161 to be retracted by the spring 170 to its repose position disposed away from the shaft 1 in accord with a feature of the invention. The pin 166 will then project into the notch 167 to lock the link 152, cams 14, 15 and valves 131 and 132 in their respective positions last assumed.

Upon venting, as above described, of the chamber 137 in the directional interlock device 8, fluid under pressure will release from the chamber 32 in the fuel cut-off cylinder device 6 by way of the pipe 301, communication 119 in the relay valve device 9, the pipe 302 and said chamber 137 to release said fuel cut-off cylinder device to allow the fuel control shaft 3 to be moved for effecting supply of fuel to the engine for running same in its astern direction.

It will be appreciated that each time a reversal in the direction of operation of the engine is called for by establishment of pressure in one of the control pipes 19, 20 while venting the other of said pipes to atmosphere, as in a snap or flash reversal while the engine is operating, the inverse double check valve device 401 in conjunction with cylinder device 5 will so control operation of the relay valve device 400 as to prevent supply of fluid under pressure from the chamber 137 in interlock device 8 from reaching the pressure chamber 157 in said device 8 until the cam shift piston 16 has moved from its one position to its opposite position to condition the engine for operation in the direction opposite to that in which it is running. According to a feature of the invention, by means of such an arrangement, operation of the piston 154 in the interlock device 8 is thus delayed to allow the shaft 1 to slow down while turning in its original direction with fuel supply cut-off to the engine before the shoe 161 is moved into engagement with said shaft 1, thereby reducing the amount of wear on said shoe over that wear which said shoe otherwise would sustain if moved into engagement with said shaft earlier at higher speed.

All other parts of the apparatus will function as described previously in relation to Fig. 1.

DESCRIPTION—FIG. 3

According to the structure shown in Fig. 3, I provide a relay valve device 500, which, for sake of illustration, may be alike schematically to the relay valve device shown in detailed section in Fig. 5. The relay valve device 500 in Fig. 3 is adapted to be incorporated in the apparatus shown in Fig. 1 to delay supply of fluid under pressure to the pressure chamber 157 in the directional interlock device 8 and to effect quick release of such fluid under pressure from said pressure chamber.

According to this feature of the invention, in the relay valve device 500, its control chamber 202 is connected to the pipe 305 and thereby to the chamber 137 in the directional interlock device 8, its chamber 204 is connected to atmosphere by way of such as a pipe 501, its chamber 205 is connected to the pipe 305' and thereby to the pressure chamber 157 in said directional interlock device, and its chamber 206 is connected to a source of supply of fluid under pressure such as the control supply pipe 40.

In operation of the apparatus shown in Fig. 1 and embodying the relay valve device 500 of Fig. 3 as above described, when fluid under pressure is supplied to the chamber 137 in the directional interlock device 8, as will be effected when a reversal in direction of operation of the engine is called for, such fluid under pressure will flow from said chamber 137 via the pipe 305 to the control chamber in the relay valve device 500 which relay valve device will then respond, substantially upon attainment of full control line pressure, to disestablish its communication 118, which at the time will be connecting the pipe 305' and hence the chamber 157 in the directional interlock device 8 to atmosphere via pipe 501, and to establish its communication 119 which connects the pipe 305' to the supply pipe 40. Fluid under pressure will then flow from the supply pipe 40, through the communication 119 in the relay valve device 500, and the pipe 305' to the pressure chamber 157 in the directional interlock device 8 to actuate the piston 154 to cause engagement of the shoe 161 with the engine crank shaft 1. As soon as the direction of rotation of the crank shaft 1 is in accord with position of the operator's control lever 44, the valves 131 and 132 will be caused to assume positions, as aforescribed herein, to effect disconnection between the chamber 137 and whichever of the control pipes 19, 20 is charged at the time and connection of said chamber 137 to the other vented control pipe. Fluid under pressure will then release from the control chamber in the relay valve device 500 to cause same to disestablish its communication 119 connecting the pipe 305' to the supply pipe 40 and to establish its communication 118 which vents said pipe 305' to atmosphere by way of the pipe 501. Fluid under pressure will then release from the chamber 157 in the directional interlock device 8 directly by way of the pipe 305' and the relay valve device 500 to allow for rapid retraction of the shoe 161 to its repose position disposed away from the shaft 1. It will be seen that the shoe automatically is retracted upon turning of the engine crank shaft 1 in its proper direction in accord with position of the operator's control lever 44 and that such retraction may be prompt by virtue of a local release of fluid under pressure from the chamber 157 by way of the relay valve device 500 which may be mounted on or adjacent to the directional interlock device.

It should be pointed out that through exchange in the relay valve device 500 of control springs 216 of different spring values, the time at which the relay valve device 500 will trip to effect operation of shoe 161 subsequent to initial movement of the operator's lever 44 to a new position may be changed as desired, a heavy control spring 216 affording a delay until the pressure of fluid supplied to the control chamber from one or the other of the control pipes 19, 20 builds up substantially to its maximum value. By means of the relay valve device 500, therefore, a delay in operation of the directional interlock shoe 161 similar to the delay afforded by employment of the structure shown in Fig. 2 may be provided to save shoe wear. At the same time, a heavy control spring 216 in the relay valve device 500 will allow for rapid release of the directional interlock shoe 161 away from the shaft since only a slight reduction in pressure of fluid in the control chamber will open the pressure chamber 157 in device 8 to atmosphere directly by way of said relay valve device rather than by way of the chamber 137, chamber 133 or 134, control pipe 19 or 20, and the operator's control device 7 as in operation of the apparatus as shown in Fig. 1 without the employment of the relay valve device in Fig. 3.

SUMMARY

It will be seen that I have provided engine control apparatus employing a direction sensing interlock device which will substantially minimize wear on the friction shoe of such device by limiting the time that said shoe is held in engagement with the engine crank shaft.

Having now described the invention, what I claim as new and desire to secure by Letters Patent, is:

1. In combination, a motion reversible member, two control pipes, a delivery chamber, control means for effecting supply and release of fluid under pressure to and from either of said two control pipes selectively, valve means conditionable according to direction of motion of said member to selectively establish connection between said delivery chamber and one or the other of said control pipes, direction sensing means operatively connected to said valve means and movable by engagement with said member, and fluid pressure means operable in response to supply of fluid under pressure to said delivery chamber to effect movement of said direction sensing means into engagement with said motion reversible member.

2. In combination, a motion reversible member, two control pipes, a delivery chamber, control means for effecting supply of fluid under pressure to either of said control pipes selectively while venting the other of said control pipes, valve means movable to one position or to another position to either establish connection between said delivery chamber and a particular one of said control pipes or between said delivery chamber and the other of said control pipes, direction sensing means movable by engagement with said motion reversible member in one direction or a reverse direction to effect movement of said valve means to said one position or to said other position, respectively, and fluid pressure means responsive to supply and release of fluid under pressure to and from said delivery chamber to effect movement of said direction sensing means into and out of engagement with said motion reversible member, respectively.

3. In combination, a reversible engine crank shaft rotatable in an ahead direction or in an astern direction, an ahead control pipe, an astern control pipe, a delivery chamber, control means operable to an ahead position to effect supply of fluid under pressure to said ahead control pipe while venting said astern control pipe and to said astern position to effect supply of fluid under pressure to said astern control pipe while venting said ahead control pipe, valve means movable to one position or to another position to establish connection between said delivery chamber and said astern control pipe or said ahead control pipe, respectively, direction sensing means movable by engagement with said shaft when rotating in the ahead direction to effect movement of said valve means to said one position and when rotating in the astern direction to effect movement of said valve means to said other position, and piston means responsive to supply and release of fluid under pressure to and from said delivery chamber to effect movement of said direction sensing means into and out of engagement with said shaft, respectively.

4. In combination, a reversible engine crank shaft rotatable in an ahead direction or in an astern direction, an ahead control pipe, an astern control pipe, a delivery chamber, control means operable to an ahead position to effect supply of fluid under pressure to said ahead control pipe while venting said astern control pipe and to said astern position to effect supply of fluid under pressure to said astern control pipe while venting said ahead control pipe, valve means movable to one position or to another position to establish connection between said delivery chamber and said astern control pipe or said ahead control pipe, respectively, direction sensing means movable by engagement with said shaft when rotating in the ahead direction to effect movement of said valve means to one position and when rotating in the astern direction to effect movement of said valve means to said other position, piston means responsive to supply and release of fluid under pressure to and from said delivery chamber to effect movement of said direction sensing means into and out of engagement with said shaft, respectively, and engine fuel cut-off means operable in response to supply of fluid under pressure to said delivery chamber.

5. In combination with a source of fluid under pressure and a reversible engine crank shaft rotatable in an ahead direction or astern direction, an ahead control pipe, an astern control pipe, a delivery chamber, an operator's control device comprising an operator's lever movable to an ahead position to effect supply of fluid under pressure from said source to said ahead control pipe and venting of said astern control pipe, to a stop position to effect venting of both the ahead and astern control pipes and to an astern position to effect supply of fluid under pressure from said source to said astern control pipe and venting of said ahead control pipe, valve means movable to one position to connect said delivery chamber to said ahead control pipe or to another position to connect said delivery chamber to said astern control pipe, direction sensing means movable by engagement with said shaft to effect movement of said valve means to said one position or to said other position according as to whether said shaft is rotating in its ahead or in its astern direction, respectively, piston means responsive to supply and release of fluid under pressure to and from said delivery chamber to

effect movement of said direction sensing means into and out of engagement with said shaft, fuel cut-off means responsive to supply of fluid under pressure to a pressure chamber to effect termination of supply of fuel to the engine, relay valve means responsive to supply of fluid under pressure to a control chamber to establish a first communication to contact said pressure chamber to said delivery chamber and to release of fluid under pressure from said control chamber to disestablish said first communication and establish an alternate communication to connect said pressure chamber to said source of fluid under pressure, and a double check valve device having two inlet openings connected to the ahead and astern control pipes, respectively, and an outlet opening connected to said control chamber.

6. In combination, a motion reversible member, two control pipes, a delivery chamber, control means for effecting supply and release of fluid under pressure to and from either of said two control pipes selectively, valve means conditionable according to direction of motion of said member to selectively establish connection between said delivery chamber and one or the other of said control pipes, direction sensing means operatively connected to said valve means and movable by engagement with said member, fluid pressure means operable in response to supply of fluid under pressure to said delivery chamber to effect movement of said direction sensing means into engagement with said motion reversible member, and timing means to delay said response.

7. In combination, a reversible engine crank shaft, two control pipes, a delivery chamber, control means for effecting supply and release of fluid under pressure to and from either of said two control pipes selectively, engine reversing means movable to assume one position or another position in response to selective supply of fluid under pressure to said control pipes, respectively, valve means conditionable according to direction of motion of said shaft to selectively establish connection between said delivery chamber and one or the other of said control pipes, direction sensing means operatively connected to said valve means and movable by engagement with said shaft, fluid pressure piston means operable in response to supply of fluid under pressure to said delivery chamber to move said direction sensing means into engagement with said shaft, and timing means including inverse double check valve means and relay valve means to prevent response of said piston means during movement of said engine reversing means.

8. In combination, a reversible engine crank shaft rotatable in ahead or astern directions, an ahead control pipe, an astern control pipe, a delivery chamber, engine reversing control means having ahead and astern positions for effecting supply of fluid under pressure selectively to said ahead control pipe and to said astern control pipe, respectively, friction means movable in one direction or an opposite direction by engagement with said shaft when rotating ahead or astern, respectively, valve means conditioned by said friction means when moved in said one direction or said opposite direction to selectively connect said delivery chamber to said astern control pipe or to said ahead control pipe, respectively, fluid pressure piston means responsive to supply of fluid under pressure to a pressure chamber to move said friction means into engagement with said shaft and upon release of fluid under pressure from said pressure chamber to retract said

friction means away from said shaft, and relay valve means responsive to supply of fluid under pressure to said delivery chamber to supply fluid under pressure to said pressure chamber and responsive to release of fluid under pressure from said delivery chamber to release fluid under pressure from said pressure chamber.

9. In combination with a source of fluid under pressure, a friction shoe adapted for frictional engagement with a reversible rotatable shaft to be moved tangentially by such engagement in one or an opposite direction according to direction of shaft rotation, a pressure chamber, piston and return spring means operatively connected to said friction shoe responsive to pressure of fluid supplied to said pressure chamber to advance said shoe in a shaftwise direction and responsive to dissipation of such pressure in said pressure chamber to retract said shoe in a counter-shaftwise direction, one control chamber, another control chamber, a delivery chamber, valve means operably connected to said shoe adapted to selectively establish a fluid pressure communication between said one or said other control chamber and said delivery chamber according to tangential movement of said shoe in its one or opposite direction, respectively, a fluid pressure conduit connecting said pressure chamber to said delivery chamber, one control pipe and another control pipe connected to said one control chamber and said other control chamber, respectively, and an operator's control valve device having an operator's handle movable in a direction corresponding to tangential movement of said shoe in its said one direction to establish connection between said source and said one control pipe and between the atmosphere and said one control pipe and movable in a direction corresponding to tangential movement of said shoe in its said other direction to establish connection between said source and said one control pipe and between atmosphere and said other control pipe.

10. The combination as set forth in claim 9 including a positioning piston pressure chamber, a positioning device comprising positioning piston and return spring means responsive to pressure of fluid supplied to said positioning piston pressure chamber to assume one position and responsive to dissipation of such pressure in said piston pressure chamber to assume another position, a control chamber, relay valve means responsive to supply and release of fluid under pressure to and from said control chamber to selectively establish fluid pressure communication between said piston pressure chamber and either said delivery chamber or said source, respectively, and double check valve means responsive to establish connection between said control chamber and whichever of the one and other control pipes is charged with fluid under pressure.

11. The combination as set forth in claim 9, including a control chamber relay valve means interposed in said fluid pressure conduit responsive to supply and release of fluid under pressure to and from said control chamber to selectively establish fluid pressure communication between said pressure chamber and either said delivery chamber or atmosphere, respectively, a cam shift cylinder comprising a reciprocable piston dividing the interior of said cylinder into two pressure chambers connected to the two control pipes, respectively, said cylinder having two spaced apart ports opening to the inner cylinder surface on which said piston slides, said ports being disposed so that both open to one or the other side

23

of said piston when same attains one or the other of two opposite extreme positions, respectively, and an inverse double check valve device having opposite inlets connected to said ports, respectively, and an outlet connected to said control chamber, operable to supply fluid under pressure to said control chamber only when both inlets are pressurized and to vent said control chamber when either or both inlets are vented.

12. The combination as set forth in claim 9, including a control chamber connected to said delivery chamber, relay valve means interposed in said fluid pressure conduit responsive to supply and release of fluid under pressure to and from

24

said control chamber to selectively establish communication between said pressure chamber and said source or atmosphere, respectively.

RALPH T. WHITNEY.
